DESIGN FOR A DIAL CASING FOR THERMOMETERS OR THE LIKE

George E. Ford, Rochester, N. Y., assignor to
Rochester Manufacturing Co., Rochester,
N. Y.

Application April 13, 1939, Serial No. 84,263

Term of patent 7 years

To all whom it may concern:

Be it known that I, George E. Ford, a citizen of Canada, residing at Rochester, in the county of Monroe and State of New York, have invented a new, original, and ornamental Design for a Dial Casing for Thermometers or the like, of which the following is a specification, reference being had to the accompanying drawing, forming a part thereof.

Figure 1 is a top view of the dial casing for thermometers or the like, showing my new design.

Figure 2 is a front elevation thereof.

Figure 3 is a side elevation thereof.

I claim:

The ornamental design for a dial casing for thermometers or the like, as shown.

GEORGE E. FORD.
